J. W. NASMITH

COMBING MACHINE

Filed Sept. 3, 1924

UNITED STATES PATENT OFFICE.

JOHN WILLIAM NASMITH, OF MANCHESTER, ENGLAND, ASSIGNOR TO NASMITH'S PATENTS LIMITED, OF MANCHESTER, ENGLAND.

COMBING MACHINE.

Application filed September 3, 1924, Serial No. 735,652, and in Great Britain May 22, 1924.

In the specification to United States Patent No. 1,466,846 granted to me there is described a feed nipper for a Nasmith combing machine which, after detaching has been completed, draws back into the said nipper a certain amount of the lap from behind the top comb before the nipper closes on the tuft to hold it during the next passage of the cylinder needles. Although this apparatus gives excellent results it requires to be adjusted with great precision. The amount of material drawn back cannot be adjusted satisfactorily, as alteration in the time of opening the feed nipper during the backward movement also alters the time of closing during the forward movement to begin the feed, and, as a consequence, the amount of material fed.

The present invention has for object the removal of the defect above indicated by making the point of opening of the feed nipper during the backward movement quite independent of the point of closing during the forward stroke, and to provide mechanism which will allow of the regulation, in a simple and exact manner, of the amount of material drawn back into the nipper and consequently of the amount of waste taken out, this regulation not affecting in any way the amount fed at each stroke, and which amount can in turn, be regulated independently of the amount drawn back. My invention contemplates further the provision of means whereby the feed on any of the six combing heads, or all of the six when desired, may be thrown out of action, and further, means for altering the position of the feed nipper in its relation to the jaw of the main nipper on all six heads simultaneously.

In carrying the invention into effect I provide the main nipper jaws, the lower main nipper plate having a backward and forward movement as described in specification to my prior patent. Upon this plate or on a member attached thereto I pivot a lever bearing the upper feed nipper jaw, which latter is normally held against the lower feed nipper jaw by spring tension. Contact means are provided against which during the backward movement of the main nipper, and hence of the upper feed nipper jaw-bearing lever, the said lever bearing the upper feed nipper jaw abuts, so that the upper feed nipper jaw is raised against the spring tension. During the return or forward move-

ment the contact means are varied in relation to the lever so that the time at which the spring means will again take control to close the upper feed nipper may be varied by adjustment of the point at which the levers will lose contact with the contact means which caused the upper feed nipper to open.

Conveniently the lower feed nipper jaw may also be mounted on a lever which is pivoted upon the main lower nipper plate or on a member borne thereby. Restraining means are provided for this lever so that as the main lower nipper plate swings the lower feed nipper will move also, but at a different rate of speed to the main lower nipper plate, as required by the functions of the apparatus.

Further, by the arrangement proposed the feed of one or all of the combing heads may be rendered inoperative as desired by merely removing the contact means out of the way of each lever bearing the upper feed nipper jaw, the latter in that case not opening during the swing of the main lower nipper plate.

A very convenient means for carrying the invention into effect will now be fully described, reference being had to the accompanying drawings, wherein:—

Figure 1 is a longitudinal section elevation through one head of a combing machine of the Nasmith type; Figure 2 is a partial position of the organs at one end of such head, it being understood that there is a corresponding set of these members at the other end of the head; and Figure 3 is a detail of mechanism for putting the feed in any one head out of action.

Referring to Figure 1, O indicates the combing cylinder, shown diagrammatically, and D the detaching roller. N is the pivot upon which the nipper arms N¹ swing to and fro. Bolted to the arms N¹ are the uprights N², these uprights being united by a bridge B to which is secured the lower jaw P² of the main nipper. The point of this lower jaw traverses an arc indicated in dotted lines at C² between the radii C and C¹, being operated by the usual connections (not shown in the drawings) from the oscillating nipper shaft W.

At each end of the bridge B is formed a boss these bosses bearing fixed studs J. The arms of the top nipper jaw are pivoted on these studs, but they are not shown, as

their description is not necessary for the explanation of the present invention, and their omission avoids complication in the drawings.

5 Upon the studs 1 are also pivoted freely the levers L, one at each side of the nipper. Solid with or secured to these levers L are the short arms L¹ bearing the fixed pins 2. The lower ends of the levers L are connected by rods 8 to a swivel 9 pivoting on the lever arm 10 keyed to a shaft 11, which shaft is fixed when the apparatus is in operation. Upon the pins 2 are also pivoted freely bell crank arms 3 which carry the upper 10 jaw F¹ of the feed nipper. The lower ends of these arms 3 are connected by a rod 12 centrally of which is fitted a bowl 13. A spring S connects the rod 12 to a pin 23 on a lever 24 on the shaft W, this spring therefore keeping the jaw F¹ tightly pressed downwards on to the lower jaw F of the feed nipper. This lower jaw F is secured to arms 4 pivoting at one end on the pins 2 and at the other end on pins 5 fixed in a link 6 15 which swings freely on pin 7 secured to the cheeks N¹.

The pins 1 move to and fro with the nipper plate P² along an arc indicated in dotted line at A—A¹ and obviously, if the levers L 20 were not controlled the whole system would swing undisturbed with the pins 1 and lower jaw F of the nipper remaining in the same relation to the plate P². The arrangement of the swivelling rods 8 however compels the 25 lower ends of the levers L to follow an arcuate path indicated at R—R¹, around the centre 9, as the pins 1 traverse their arcuate path A—A¹. Levers L therefore pivot on the pins 1 and as a result the pins 2 and the 30 members 3 and 4 are drawn backwards and change their relative positions with regard to plate P². The bowl 13 on shaft 12 would normally, in the operation above described, follow an arc indicated in dotted lines at 35 N². Pins 2 moving backwards, however, as the point of the nipper plate P² swings along its arc A—A¹, the bowl departs from this arcuate path and meets an inclined face 16^a at the dotted line position 13^a, forcing it 40 to deviate further from such path in its progress to dotted line position 13^b. The top jaw F¹ of the feed nipper is thus raised around the centre 2 against the tension of spring S. It will be evident therefore that 45 the position of inclined face 16^a in relation to the arcuate normal path of the bowl 13 will determine the time of opening of the upper jaw F¹ during the backward movement of the main nipper when the feed nipper opens to release the lap, to regulate the 50 amount of material drawn back.

The inclined face 16^a is formed upon or secured to the extremity of an arm 16 pivoting on shaft 15 and bolted to an arm 14 55 keyed on said shaft 15. A set screw or the

like 17 in arm 16 and traversing a slot 18 18 in arm 14 serves to adjust the arm 16 in relation to arm 14. Thus, the position of inclined face 16^a may be regulated in relation to the path of the bowl 13.

If the shaft 15 and its connected parts, and arm 16, remained stationary it will be seen that the inclined face 16^a being stationary, the upper feed nipper jaw F¹ would open and close at the same point owing to the action of the bowl 13 against such fixed face 16^a in both directions of traverse of the said bowl, there being thus no effective feed. The lever 16 is however controlled from the cam M, operating the lever arm 19 through cam bowl 20 pivoted on the end of said lever arm, the other end of the lever arm 19 being mounted on shaft 15 and adjustably secured to the shoe 21 provided with set screw 22 and also free on the shaft 15. Solid with member 21 is the arm 27 provided with two holes 28 and 29. A lever 30 is keyed on the shaft 15 provided with a hole adapted to register with either of the holes 28 and 29 as desired, a pin passing 80 through the two corresponding holes thus securing members 27 and 30 in either of two positions. During the rearward movement of bowl 13, the bowl 20 is running on the semi-circular face of the cam M and there is therefore no motion of the arm 16 and its inclined face 16^a. It is obvious that cam M could be moved considerably around its centre without affecting the face 16^a, that is, without altering the time in the backward stroke when bowl 13 makes contact with such inclined face say at the position 13^a, and this time can be altered by changing the relative position of arm 16 to lever 14 by means of the pin and slot 17 and 18.

The cam is regulatable upon its shaft. On the forward nipper stroke the bowl 20 engages the effective or actual cam surface thereof, thus withdrawing the inclined face 16^a by movement of the arm 16. It will 100 thus be seen that by adjustment of the cam M the time that the bowl 13 will leave the face 16^a can be easily and accurately regulated and long before the bowl 13 again returns to make contact with such face on the inward stroke of the feed nippers the said face has been restored to its normal position for that purpose by the bowl 19 coming upon the circular edge of the cam M. Effectively therefore the time of opening the feed 105 nipper can be varied in regard to the time of closing, by changes in the relation of the arcuate paths traversed by bowl 13 on the backward and forward nipper stroke, and this relation between the paths can be varied 110 as desired as above described. The amount of material drawn back within the nipper can therefore as a result be varied in relation to the amount fed forward.

The feed nippers can be adjusted in rela- 115

tion to the points of their bottom plates P^2 by the adjusting nuts on the rods 8. When the feed nippers of each combing head are thus equally adjusted they can all be moved further from or nearer to the said point of plate P^2 by loosening the clamping bolt 26 which passes through slot 25 in each lever 10 and turning the shaft 11 the required angular distance, bolt 26 being then again secured.

10 A method of arresting the feed on any individual combing head is shown in Figure 3 in elevation. The arm 16 bearing the inclined face 16^a has lugs 31 32 to receive pins 33 and 34. The inclined face 16^a is a separate member to arm 16 and is hinged to the latter by pins 33. A latch 35 is hinged on pin 34, and has two notches 36 formed therein. In the arm 16 is fixed a pin 37. Thus, to withdraw the face 16^a so that the bowl 13 will not make contact with it, the latch 37 is lifted and the appropriate notch allowed to drop over pin 37, no contact between bowl 13 and the inclined face thus taking place to raise the upper npper jaw F^1 .

20 To arrest the feed of all the nippers of each of the heads simultaneously or to arrest the feed of each of them individually, it is only necessary to withdraw the inclined face 16^a out of the path of bowl 13, upper npper jaw F^1 thus remaining closed.

25 As already explained, arm 27 has two holes 28 and 29 and lever 30 has one hole which may register with either of them. Normally, during the operation of the machine, the hole in arm 16 will register with hole 29, a pin passing through them holding these members together in fixed relation. 40 To withdraw each arm 16 in the combing apparatus out of contact with the bowl 13 of each head, the pin is withdrawn and the shaft 15 turned until the hole in each arm 27 registers with hole 28 in each lever 14. The pin is then passed through the two now corresponding holes and the feed on all heads is stopped.

45 I claim:—

50 1. In a combing machine an oscillatory lower npper plate, lever supports for the said plate, a pivot-bearing element mounted on the said lever supports and on the pivots of which are fulcrumed further levers to which are attached upper and lower feed npper jaws, an arm bearing a contact face adapted to oscillate to and from the oscillatory path of the free ends of the levers bearing the upper feed npper jaw, means for adjusting the said arm, and means for varying the oscillation period of the said arm in relation to the said path of the said lever ends on the forward movement of the said arm and lever ends, for the purpose hereinbefore set forth.

55 2. In a combing machine having the feed npper jaws arranged as claimed in claim 1, restraining means for the lever bearing the lower feed npper jaw to cause said lever to move around its pivot point as the main lower npper plate swings in its backward and forward movement, and a swinging support for the front end of the npper jaw, for the purpose hereinbefore set forth.

60 3. In a combing machine arranged as claimed in claim 1, contact means to move the upper feed npper jaw lever around its pivot point and to vary the relation of the contact means and lever, such means comprising an arm radially movable upon a shaft having an inclined face on the end thereof, a bowl carried by the upper feed jaw levers and making sliding contact with the inclined face during the backward movement of the levers, and a cam and rod operating the inclined face-bearing arm to alter its relation to the bowl on the forward movement only of the npper-bearing lever to vary the length of contact between the bowl and contact face of the forward movement in relation to the length of contact on the backward movement.

65 4. In a combing machine having the features claimed in claim 1, an arm and a lever to which the contact bearing arm is adjustably secured by a pin and slot to adjust the contact face in relation to the path of the ends of the upper feed npper jaw bearing levers, substantially as set forth.

70 5. In a combing machine having the features claimed in claim 1, a lever pivoting on a cam rod shaft, an arm bearing the contact face, holes in the arm and lever, and a pin to pass through a hole in one member and through either of two holes in the other member, substantially as and for the purpose hereinbefore set forth.

75 6. In a combing machine having the features claimed in claim 1, an arm bearing the contact face, such contact face being a member hinged to the arm, a latch portion on the contact face, such latch having a plurality of recesses therein, and a stud on the contact face-bearing arm to fit in either of the recesses in the latch substantially as and for the purpose hereinbefore set forth.

80 7. In a combing machine having the nppers arranged as claimed in claim 1, a swiveling rod attached to the lower end of the levers bearing such jaw, a lever having a swivel bearing for such rod, a shaft supporting such swivel bearing lever, an arcuate slot in the swivel bearing lever and an adjusting rod passing through such slot, substantially as and for the purpose hereinbefore set forth.

85 In testimony whereof I have hereunto set my hand.

JOHN WILLIAM NASMITH.
